UNITED STATES PATENT OFFICE

LOUIS KUEHN, OF MILWAUKEE, WISCONSIN, ASSIGNOR, BY MESNE ASSIGNMENTS, TO
MILCOR STEEL COMPANY, OF MILWAUKEE, WISCONSIN, A CORPORATION OF DELA-
WARE

CORNER MOLDING

Application filed November 4, 1927. Serial No. 230,963.

This invention relates to corner molding or ornamental corner strips especially adapted for use in filling the angle or corner presented at the intersection of a ceiling with the side walls of a room.

One of the objects of the present invention is to provide a corner molding or corner strip of this character which may be constructed of metal and which is provided with ridges or 10 corrugations serving the dual purpose of enhancing the ornamental appearance of the molding and of providing a positive interlock with the plaster of the ceiling and of the side wall.

15 Another object of the invention is to provide a corner molding or ornamental corner strip of this character and which has a body plate so formed as to give the corner molding decorative and ornamental lines and to provide an enclosed passage for the reception of piping, wires, or the like.

20 A further object is to provide a corner molding or corner strip made up of similar sections adapted to be interfitted to present the appearance of a single continuous piece of molding.

25 Another object is to provide a corner strip or corner molding which is made up of a single piece of metal having an ornamented body and anchoring wings of expanded metal.

30 Other objects and advantages reside in certain features of the construction, arrangement and combination of parts which will be hereinafter more fully described and particularly pointed out in the appended claims, 35 reference being had to the accompanying drawings forming a part of this specification, and in which:

40 Figure 1 is a perspective view showing a portion of a room equipped with a corner molding or corner strip embodying the present invention;

Figure 2 is a view in transverse vertical section showing the molding of Figure 1;

45 Figure 3 is a view in elevation looking toward the right in Figure 2; and

Figure 4 is a fragmentary sectional view showing how the adjacent ends of sections of the molding are interfitted.

50 Referring to the drawings, the numeral 1

designates the side walls of the room and number 2 the ceiling thereof. The ornamental corner strip or corner molding is designated generally at 3 and, as shown in Figure 1, is positioned at the angle or corner 55 between the side walls and the ceiling, the corner strip filling this angle and relieving the sharp intersection of the ceiling and side walls. This corner molding is made up of sections of suitable length which are inter- 60 fitted as will hereinafter more fully appear. The sections are of similar construction so that a description of one will apply to all.

Each section of the molding comprises a 65 transversely curved or arched body plate 5 formed along its margins with a plurality of lengthwise ridges or corrugations 6. These ridges or corrugations 6 are of V-shaped cross section and are integral with the body plate 5. Beyond the ridges 6 anchoring 70 wings 7 of expanded metal are provided, these wings 7 also being cut from the same piece of metal that is utilized to make up the body plate 5 and ridges 6.

In placing the molding in position one of the wings 7 is incorporated in the side wall and the other wing 7 is incorporated in the ceiling with the ridges 6 and body plate 5 filling the angle between the side wall and the ceiling and defining with the side wall and ceiling a passage 8 for the reception of piping, wires, or the like. The expanded metal wings 7 may overlap and be fastened to the metallic or other lathing employed and it is adapted to and does interlock with the plaster P embodied in the side walls and ceiling. The outer ridges 6 have their outer walls 6' undercut with respect to the surfaces of the wall or ceiling in which they are embodied and this undercut arrangement of the surfaces 6' affords a positive interlock with the plaster as more clearly shown in Figure 2.

In order to adapt the sections of the molding for proper interfiting the body portions and wings of each section have inwardly depressed extensions 5^a and 6^a at one end of the section but the wings 7 are cut away so as to terminate at the juncture of the main portion of the sections and the extensions 5^a and 6^a. The other end of each section is shaped 95

like the body of the section. This provides for an interlock or interfit of the character shown in Figure 4, the plain end of the section overlapping the inwardly depressed ex-
5 tension of the adjacent section.

The invention claimed is:

1. A molding for a re-entrant corner having a transversely curved body plate for providing a convex surface in the corner, longitudinal marginal ridges of V-shape in cross section integral with the body plate and wings of expanded metal extending from the outer-most edges of the outer marginal ridges, the wings extending at an angle to the contiguous ridges, the outsides of the ridges being undercut to define pockets adapted to interlock with plaster.
- 10 2. A section of sheet metal corner molding including a transversely curved body plate, longitudinal marginal ridges on the body plate, wings of expanded metal extending from the ridges, the body plate and ridges having an inwardly depressed extension at one end, said wings terminating short of said 15 inwardly depressed tension.
- 20 3. A metal corner molding for use between the ceiling and the side wall of a building structure and comprising a body plate adapted to fill the angle of intersection of the side wall and ceiling and formed with marginal ridges, and wings integral with the outermost ridges of the body plate and adapted to be embedded in the plaster of the side wall and the ceiling for supporting the molding in 25 position, said wings coacting with said outermost ridges to form plaster retaining pockets.
- 30 4. A metal corner molding for use between the ceiling and side wall of a building structure and comprising an inwardly bulging convex body plate filling the angle of intersection of the side wall and ceiling but spaced therefrom to form an unobstructed passage 35 for the reception of pipe, wires, and the like, and wings connected with the body plate and extending at obtuse angles with respect to the mean plane of the body plate and at a right angle to each other and adapted to be incorporated in the ceiling and side walls to 40 support the molding in position.
- 45 60

In witness whereof, I hereto affix my signature.

LOUIS KUEHN.

CERTIFICATE OF CORRECTION.

Patent No. 1,813,173.

Granted July 7, 1931, to

LOUIS KUEHN.

It is hereby certified that error appears in the printed specification of the above numbered patent requiring correction as follows: Page 2, line 25, claim 2, for "tension" read extension; same page, line 40, claim 4, for "inwardly" read outwardly; and that the said Letters Patent should be read with these corrections therein that the same may conform to the record of the case in the Patent Office.

Signed and sealed this 1st day of September, A. D. 1931.
